(57) **CLAIM**

The ornamental design for an earphone as shown and described.

DESCRIPTION

- 1.1 : Front
1.2 : Back
1.3 : Left
1.4 : Right
1.5 : Top
1.6 : Bottom
1.7 : Perspective

This design product is an earphone; The design product is used for connecting electronic and/or digital products with wireless signals for transmitting audio signals and playing sound; The line shading in the figures represents contour and not surface ornamentation.

1 Claim, 7 Drawing Sheets
